United States Patent Office

Des. 186,356
Patented Oct. 20, 1959

186,356

SINK

Claus L. Sporck, Cincinnati, Ohio, assignor to Lodge & Shipley Company, Cincinnati, Ohio, a corporation of Ohio

Application March 11, 1959, Serial No. 54,934

Term of patent 14 years

(Cl. D4—2)

Fig. 2

I claim:

The ornamental design for a sink, substantially as shown.
